UNITED STATES PATENT OFFICE

119,876

DESIGN FOR A COMBINED WASHING MACHINE AND WRINGER

David Chapman, Chicago, Ill., assignor to The
Apex Electrical Manufacturing Company,
Cleveland, Ohio, a corporation of Ohio

Application December 29, 1939, Serial No. 89,196

Term of patent 7 years

To all whom it may concern:

Be it known that I, David Chapman, a citizen
of the United States of America, residing at Chi-
cago, in the county of Cook and State of Illinois,
have invented a new, original, and ornamental
Design for a Combined Washing Machine and
Wringer, of which the following is a specification,
reference being had to the accompanying draw-
ing, forming a part thereof in which the figure

shows a perspective view of a combined washing
machine and wringer. The side of the combined
washing machine and wringer not shown is sub-
stantially the same as the side shown.

I claim:

The ornamental design for a combined washing
machine and wringer, as shown and described.

DAVID CHAPMAN.
